No. 625,997.

Patented May 30, 1899.

B. J. BALLIETT.

SUSPENDERS.

(Application filed Nov. 14, 1898.)

(No Model.)

UNITED STATES PATENT OFFICE.

BYRON J. BALLIETT, OF MANSFIELD, OHIO.

SUSPENDERS.

SPECIFICATION forming part of Letters Patent No. 625,997, dated May 30, 1890.

Application filed November 14, 1898. Serial No. 696,396. (No model.)

To all whom it may concern:

Be it known that I, BYRON J. BALLIETT, a citizen of the United States, residing at Mansfield, in the county of Richland and State of Ohio, have invented certain new and useful 5 Improvements in Suspenders; and I do hereby declare that the following is a full, clear, and exact description of the same, reference being had to the annexed drawings, making a part 10 of this specification, and to the letters of reference marked thereon.

The present invention has for its object to provide suspenders possessing both strength and durability and which can be manufactured at a comparatively small cost, also its 15 special construction securing ease and comfort to the wearer.

The invention has relation to that class of 20 suspenders in which is provided a cord having sliding connections and an extensible or elastic band; and the purpose thereof is to provide means whereby such extensible or elastic band is dispensed with, thereby materially simplifying the construction of the 25 suspenders in reducing the number of parts and rendering them more effective in giving comfort to the wearer.

The invention consists in suspenders constructed substantially as shown in the drawings and hereinafter described and claimed.

Figure 1 of the drawings is a rear elevation of 30 suspenders constructed in accordance with my invention; Fig. 2, a view, on a small scale, showing the rear part of the suspenders attached to the back of the wearer; Fig. 3, a detail view, in perspective and on an enlarged scale, of the quadruple hanger.

In the accompanying drawings, A B represent the suspender-straps, of any suitable material and of any preferred construction, and 40 which are provided at their front ends with suitable straps or cords C, having looped ends to engage the buttons on the trousers. The rear ends of the suspenders are provided with 45 suitable means or devices D for receiving the continuous or endless strap or cord E, so that they will work loosely therein.

The several parts of the suspenders above referred to may be variously modified or 50 changed, as found most desirable, without departing from the principle of my invention.

The essential feature of the invention re-

sides in the quadruple hanger F, as shown more clearly in Fig. 3 of the drawings, together with the strap or cord E, engaging 55 therewith. This quadruple hanger consists of four suitably-hinged loops G, through which the strap or cord E passes, as shown in Fig. 1 of the drawings. These loops G may be hinged to any suitable object which 60 will form a common center for the loops, such as the wire H or other convenient device. Through the medium of this quadruple hanger the slightest strain or pull on either shoulder-strap will be communicated to the 65 whole, and at once relief is given to the part where the strain is applied, thus practically eliminating any resistance.

The four loops G hold the strap or cord E 70 in a uniform position and admit of the strap or cord moving freely in the loops and allow free movement of the strap or cord in the natural adjustment of the suspender. As will be seen from Figs. 1 and 3, these four loops are all mounted directly on the central device 75 H and are disposed about the same so as to assume the same relative position as to the said device and each other. The strap or cord E passes through each of the loops, and by this means I am enabled to dispense with 80 the elastic strap heretofore employed for a connection between the lowermost loop and the wire upon which the other three are hung. I have found that in addition to simplifying the construction I attain better results in that 85 the cord thus arranged has an even pull in all directions and the suspenders are more comfortable to the wearer.

The arrangement of the strap or cord E 90 brings the same in the hollow of the back of the wearer, where it will not be felt when leaning against a chair-back or other support, and the strap or cord loosely engaging with the quadruple hanger every motion of the shoulder or trousers band is equalized to the 95 greatest possible degree, thereby saving the buttons and the discomfort to the wearer caused by any binding over the shoulders, as in the suspenders of the ordinary construction.

Having now fully described my invention, what I claim as new, and desire to secure by Letters Patent, is—

1. A pair of suspenders comprising the

shoulder-straps, a quadruple hanger comprising four hinged loops arranged at substantially equal distances apart and all directly upon a common support, and a strap or cord 5 engaged with all of said loops and with the rear ends of the shoulder-straps and adapted to engage the buttons upon the rear of the trousers-band, as set forth.

2. In a suspender, a quadruple hanger consisting of four loops mounted at substantially equal distances apart directly upon a central

supporting device and extending from and mounted to swing upon all four sides of said supporting device, as shown and described.

In testimony that I claim the above I have 15 hereunto subscribed my name in the presence of two witnesses.

BYRON J. BALLIETT.
